CLAIM

The ornamental design for a waffle maker with rotation provision for even cooking as shown and described.

DESCRIPTION

FIG. 1 is a top, front perspective view of a waffle maker with rotation provision for even cooking showing our new design;

FIG. 2 is a front view of the waffle maker with rotation provision for even cooking depicted in FIG. 1;

FIG. 3 is a rear view of the waffle maker with rotation provision for even cooking depicted in FIG. 1;

FIG. 4 is a left, side view of the waffle maker with rotation provision for even cooking depicted in FIG. 1;

FIG. 5 is a right, side view of waffle maker with rotation provision for even cooking depicted in FIG. 1;

FIG. 6 is a top view of the waffle maker with rotation provision for even cooking depicted in FIG. 1;

FIG. 7 is a bottom view of the waffle maker with rotation provision for even cooking depicted in FIG. 1; and,

FIG. 8 is a top, front perspective view of the waffle maker with rotation provision for even cooking depicted in an alternate configuration.

The broken lines in the drawings illustrate portions of the waffle maker with rotation provision for even cooking that form no part of the claimed design.

1 Claim, 8 Drawing Sheets
